UNITED STATES PATENT OFFICE.

ROY H. CARL, OF GREENFIELD, IOWA.

ELECTRIC SWITCH.

1,194,272.

Specification of Letters Patent.

Patented Aug. 8, 1916.

Application filed April 12, 1915. Serial No. 20,824.

To all whom it may concern:

Be it known that I, ROY H. CARL, a citizen of the United States, residing at Greenfield, in the county of Adair, State of Iowa, have invented certain new and useful Improvements in Electric Switches; and I do hereby declare the following to be a full, clear, and exact description of the invention, such as will enable others skilled in the art to which it appertains to make and use the same.

This invention relates to electric switches and particularly to that type used in conjunction with electric signs.

15 The object of the invention resides in the provision of an electric switch for use in connection with an electric sign wherein the lights are arranged to indicate a given word and the illumination of the lights controlled by the switch in such manner as to simulate the writing of the word with a pen, the switch further controlling the extinguishment of the lights in a similar manner.

25 A further object of the invention resides in the provision of a switch of the character named which will be simple in construction, efficient in use and comparatively inexpensive to manufacture.

30 With the above and other objects in view the invention consists in the details of construction and in the arrangement and combination of parts to be hereinafter more fully described and particularly pointed out in the 35 appended claim.

35 In describing the invention in detail reference will be had to the accompanying drawings wherein like characters of reference denote corresponding parts in the 40 several views, and in which—

Figure 1 is a diagrammatic view showing the improved switch associated with an electric sign wherein the lights of the sign are arranged to indicate the word Carl; Fig. 45 2, is a side view of the switch; Fig. 3, an end view of same, and Fig. 4, a central transverse sectional view.

Referring to the drawings the improved switch is shown as comprising a body 10 in 50 the form of a disk constructed of porcelain or other suitable insulating material. Suitably mounted upon one end of the body 10 are a plurality of concentrically arranged wires 11. One set of corresponding ends of

the wires 11 recede successively from the 55 outermost wire to the innermost wire, while the other set of corresponding ends of said wires successively advance from the outermost wire to the innermost wire. Pivoted centrally upon the body 10 is an arm 12 60 adapted to be rotated in any suitable manner. As this arm 12 is rotated in the direction of the arrow in Fig. 3 it will first engage the outermost wire 11, then the next wire 11 and so on until it passes into engagement 65 with all of said wires. As the rotation of the arm 12 is continued it will first pass out of engagement with the outermost wire 11 and then out of engagement with the next wire 11 and so on until the arm 12 is out of 70 engagement with all of the wires 11. This operation is effected upon each complete rotation of the arm 12. Mounted on the end of the body 10 are binding posts 13 which are connected respectively to the wires 11. 75 These binding posts are in turn connected by wires 14 with lights 15 respectively which are embodied in the sign, it being noted that the binding post connected with the outermost wire 11 is in turn connected with the 80 light 15 at the beginning of the letter "C" of the sign, while the binding post connected with the wire 11 next to the outermost wire 11 is in turn connected to the second light in the letter "C" and so on. The lights 15 are 85 also connected by wires 16 to an electric source A and this source is also connected to the arms 12 by means of a wire 17. By this construction it will be obvious that as the 90 arm 12 is rotated in the direction of the arrow in Fig. 3 the lights 15, beginning in the first light in the letter "C" of the sign, will be successively illuminated until the entire sign is illuminated. By continued rotation of the arm 12 the latter will successively pass 95 out of engagement with the wires 11, beginning at the outermost wire and thereby successively extinguish the lights 15, beginning at the first light in the letter "C", until the entire sign is extinguished.

100 What is claimed is:

A switch for electric signs comprising a disk body of insulating material, a plurality of substantially coextensive parallel spaced concentrically arranged conductors secured 105 against one end of the body, said conductors having one set of corresponding ends receding successively from the outermost conduc-

- tor inwardly, and the other set of corresponding ends advancing successively from the outermost conductor inwardly, and a switch arm pivoted to the center of the body
5 and adapted to simultaneously engage all of said conductors during a portion of its rotation.

In testimony whereof, I affix my signature, in the presence of two witnesses.

ROY H. CARL.
